UNITED STATES PATENT OFFICE.

CHARLES WAGNER, OF GRANTWOOD, AND AUGUST HORMEL, OF JERSEY CITY, NEW JERSEY.

DRYING APPARATUS FOR PLATES OF METAL AND OTHER MATERIAL.

Application filed September 29, 1920. Serial No. 413,605.

To all whom it may concern:

Be it known that we, CHARLES WAGNER and AUGUST HORMEL, both citizens of the United States, and residents, respectively, of 5 Grantwood, in the county of Bergen and State of New Jersey, and 260 Griffith Street, Jersey City, State of New Jersey, have invented certain new and useful Improvements in Drying Apparatus for Plates 10 of Metal and Other Material, of which the following is a specification.

This invention relates to improvements in drying apparatus for plates of metal and other material.

15 The present invention is an improvement upon the apparatus described in applicants' Letters Patent numbered 1,293,261 of February 4th, 1919, and applicants' prior application Serial No. 340,201 filed November 24th, 1919.

One object of this invention is the provision in a drying apparatus; comprising an elongated enclosed and heated casing having conveying means preferably movable in opposite directions therethrough to convey plates resting on one of their edges of means for automatically delivering and stacking the plates to lie flat or in horizontal position after the passage through such drying 30 casing.

Another object of our invention is to procure simple means for swinging the lower edge to enable a sliding of the plates by gravity into horizontal flat position in stacks 35 and to this end we utilize the turning movement of the conveying and carrying means of our prior patent and application in combination with a guide rail for moving or swinging the plates vertically into an inclined position from which they are adapted 40 to slide by gravity into flat stacked position.

Another object of our invention is to provide means for accelerating the delivery of such plates from the machine and still another object of our invention is to guide the throw or delivery movement to cause the plates to drop at a proper degree of angularity to prevent denting of previously stacked plates.

50 Another object of our invention is the provision in such a drying apparatus having oppositely movable conveyers of simplified means for transferring plates from one con-

veyer to the other or from a top or rearwardly-moving conveyer to a bottom or forwardly-moving conveyer.

Another object of our invention is the provision of plate-aligning rods movable in opposite directions toward the axis of the conveying compartment or compartments and adapted to contact with the opposite edges 60 of the plates and to move the same into proper alignment and into contact with the carriers, chains or transfer mechanism.

Another object of our invention is the provision of guide rails extending parallel and adjacent to the conveyer chains and adapted to enable the guiding through the conveyer compartment of a plate which has slipped or moved off the chain.

With these and other objects in view, the invention comprises the combination of members and arrangement of parts so combined as to co-act and cooperate with each other in the performance of the functions 75 and the accomplishment of the results herein contemplated, and comprises in one of its adaptations the species or preferred form illustrated in the accompanying drawings, in which:—

Fig. 1 is a plan view of apparatus embodying our invention, the top of the casing being cut away;

Fig. 2 is an enlarged side elevation of the front of the apparatus showing a portion 85 of the feed mechanism and the delivery, ejecting or stacking mechanism;

Fig. 2^a is a similar enlarged side elevation of the rear end of the machine, the casing being shown in section;

Fig. 3 is a section on the line 3—3 of Fig. 2;

Fig. 4 is a section on the line 4—4 of Fig. 2^a.

Fig. 5 is a section on the line 5—5 of Fig. 1; and

Fig. 6 is a section on the line 6—6 of Fig. 2^a.

Referring now to these drawings which illustrate a preferred embodiment of our invention, our improved plate drying apparatus embodies the following elements:—

The casing.

An elongated casing which, as shown, has 105 a metal frame 1, a casing or cover of sheet

metal 2 and a lining 3 of suitable heat resisting or insulating material such as asbestos. The casing is, as shown, closed at two sides, on top and at the rear end, while 5 it has openings at the opposite or front end to permit the feeding and delivery of plates at the same end. The casing may be heated in any suitable manner and is provided, as shown, with heaters comprising 10 perforated pipes 4 constituting burners which are adapted to receive gas or other suitable fuel from any suitable source not shown. The burners, as shown, pass through inverted U-shaped hoods 5 which assist in 15 effecting a uniform diffusion of heat.

The conveyer.

Mounted within the casing is a conveyer 20 preferably comprising a pair of endless conveyer chains 6 extending parallel and in suitable spaced relationship to each other and adapted to convey plates, as shown, in one direction or rearwardly and also suitably mounted below the conveyer 6 in suitable spaced relation thereto is another conveyer, preferably comprising a pair of endless conveyer chains 7 adapted to convey plates in the opposite direction or forwardly. These conveyer chains may be 30 mounted in any suitable manner and, as illustrated, the upper chains 6 are at their opposite ends mounted upon pairs of sprocket wheels 8 and 9 fast on shafts 10 and 11 respectively; and the lower pair of 35 chains are mounted at opposite ends upon pairs of sprockets 12 and 13 fast upon shafts 14 and 15. The shaft 10 is, as illustrated, driven synchronously with the shaft 14 from a power shaft 16 which is rotated from any 40 suitable source of power such as the pulley 17 and transmits power through the intermeshing beveled gears 18 and 19 to the worm 20 on the shaft 21 which meshes with the worm wheel 22 on the shaft 14 of the sprockets 12. On shaft 21 is also mounted a 45 sprocket 23 which transmits through the chain 24 to the sprocket 25 on the shaft 26, on which shaft 26 is mounted a worm 27 which meshes with a worm wheel 28 mounted 50 on the said shaft 10 on which the sprockets 8 are mounted. It will be obvious that this transmission causes the shafts 10 and 14 to rotate synchronously in opposite directions for the purpose of driving the conveyer-chains 6 and 7 respectively.

The carriers.

The upper pair of conveyer chains 6 have 60 suitably mounted thereon a plurality of carriers 29 which, as shown, comprise frames preferably formed of a strand of wire connected at its opposite ends to the opposite members of the pair of chains and bent intermediate their ends substantially rectan-

gular in conformation, each frame has, as 65 shown, wire reinforcements 30 and 31 secured at one end to the top and opposite sides of the carrier frame 29.

Feed mechanism.

In the preferred embodiment shown, a suitable automatic plate feed mechanism is arranged at the front of the machine and such mechanism is preferably provided with means for timing or synchronizing the 75 movement of the plates to correspond with the movement of the carriers as illustrated in our co-pending application Serial No. 340,201, the plates being fed intermittently and synchronously with the movement of 80 such carriers on feed belts 32-33 from which they are picked up by the carriers 29 as they revolve about the sprockets 8 and are permitted to slide by gravity on to the conveyer chains 6 by which they are then 85 conveyed in vertical position to the rear of the machine.

The transfer roller.

At the rear of the casing and as shown 90 between the two members of the pair of conveyer chains 6 and on the same shaft 11 on which are mounted the sprockets 9 for the said conveyer chain 6 is mounted a grooved roller 34 preferably composed of 95 three sections, as illustrated, to permit the insertion between such sections of ejecting means for positively removing the plates from the grooves in case the same fail to drop by gravity after they have travelled 100 into proper position in relation to the lower chains or in case the same become jammed in the grooves or otherwise stuck therein. The said roller 34 is, as more particularly shown, provided with radial plate grooves 35 for 105 the reception of the lower edge of the plates, which grooves preferably extend lengthwise of the roller from end to end thereof. These grooves are provided with widened 110 mouths formed by inclining the opposite walls 36 of each groove at the mouth thereof contiguous to the periphery of the roller so that the walls of adjacent grooves come to a pointed rib 37 extending lengthwise of the roller. In order that the plates may 115 drop by gravity into the radial grooves 35, the plates in their travel adjacent to the said roller 34 are lifted out of contact with the conveyer chains by the guide rods 38 which are, as shown, mounted in the cross bar 39 120 and extend over the lower roller 34 with the terminals thereof in such position that a plate when moved forwardly along such guides 38 will at the end of its travel on such guides drop by gravity into the mouth 125 36 of the radial grooves 35 and will thereafter fall down into the radial grooves 35 in the roller and will in such grooves be

carried by the roller and caused to revolve about its axis in shaft 11. During the horizontal portion of the travel of the plates, they are held and pushed along by the carriers at the rear thereof. When the plates start to revolve, however, they are swung from contact with the rear carrier into contact with the forward carrier and are supported and moved by said grooved roller 10 and forward carrier until the plate reaches a radial position below the horizontal, whereupon it will slide along its supporting forward carrier until the opposite edge thereof contacts with guide rails 40 along 15 which guide rails 40 it will travel by gravity or will be pushed by the rear carrier until the said opposite edge thereof comes into contact with the lower conveyer chains, by which it will be conveyed on its forward 20 travel through the casing, the carriers retaining the plates in upright or vertical position on such chains.

The rails 40 are preferably adjustable to enable the handling of plates of varying 25 heights without an undue amount of sliding movement between the grooved roller and such guide rails and for this purpose such rails are preferably pivoted at 40^a on the supporting bars 7^a for the upper stretch 30 of the lower conveyer chain 7. Any suitable means may be provided for adjustably moving the rails 40 about the pivots 40^a and as illustrated we provide lever arms 40^b fixed at one end on a shaft 40^c mounted in 35 suitable bearings in the casing 1. The free ends of the lever arms 40^b are pivotally connected to links 40^d which are also pivotally connected with the rails 40. Suitable means is provided for rocking the shaft 40^c and, 40 as shown, said shaft is extended at opposite ends beyond the casing and each end thereof is provided with a ratchet and pinion 40^e and a hand-rocking lever 40^f. Obviously when the lever 40^f is manipulated by 45 hand the shaft 40^c will be rocked and movement will be transmitted through the lever arm 40^b and 40^d to the rails 40 and such rails may be locked in any suitably adjusted position by means of the ratchet and pinion 50 device 40^e.

During the transfer of the plates from the upper chain to the roller 34 it is desirable to apply pressure to the top edges of such plates in order to cause the same to be forced down into the grooves 35 and for this purpose we preferably provide a pair of pivoted rods 41 which, as shown, are pivoted at 42 and have their outer ends resting on the top edges of the plates for 55 the purpose of applying pressure or weight thereto to cause the same to be forced into the grooves 35 in the roller 34.

The means for ejecting the plates from the roller grooves in case the same adhere

thereto or become jammed or stuck therein 65 preferably comprises an inclined arm 38^b which is positioned so as to intersect the arc described by the bottom of the grooves so that in case a plate or plates become stuck or jammed in a groove or grooves they will 70 be forced out of the same in their forward travel by this ejector arm 38^b which, as shown, is supported by arm 38^a from the rods 38, said supporting arm extending between the sections of the roller 34 between 75 which sections grooves 34^a are preferably made for this purpose.

The aligning mechanism.

In such travel back and forth through the 80 casing, it frequently happens that one or more of the plates get out of alignment with the others and due to vibration and other causes would, if not properly aligned, be likely to fall off the conveyer chains. For 85 the purpose of aligning the plates and obviating the aforesaid difficulties, we preferably provide at opposite sides of the path of travel of the plates upper and lower pairs of aligning rails 43 and 44 respectively. 90 These rails are preferably pivotally supported at a plurality of points on the casing and the members of a pair of aligning rails are preferably adapted to be actuated simultaneously to move toward the center of the 95 casing and thus to align the opposite edges of the plates simultaneously. In the preferred form shown, the rails are supported at their opposite ends by links 45 which are, as shown, pivotally connected to the rails 100 at their outer ends and mounted upon vertical rocking rods 46 which are connected to cause simultaneous rocking thereof in opposite directions by links 47 and 48 and the connecting rods 48^a—48^b. Any suitable 105 means may be employed to rock the vertical rods 46 to move the rails toward and away from the edges of the plates and as shown we have provided a lever 49 connected to one of said vertical rods and extending 110 through a hole 50 in the casing and having a handle portion 49^a for hand-manipulation.

While in most cases the aligning rails 44 respectively will be sufficient to prevent the plates from dropping off the chains, these 115 means require manipulation and adjustment and in order to insure the travel of an unaligned plate or one that has fallen off the chain, we preferably provide between and adjacent to the chains 6 and 7 respectively a pair of stationary guide rods 6^b. 120

At each side of the path of travel of the carrier 6 we also preferably provide doors 43^a to close up the space between the travelling plates P and the walls of the casing. 125 As shown, these doors 43^a are hinged at one side edge on the casing and are also preferably inclined in the same direction as the

links 45 and are pivoted at their opposite edges to the guide rails 43 and will therefore be rocked by such guide rails.

5 *The delivery stacking mechanism.*

At the front end of the machine, at the end of the travel of the plates, we preferably provide means such as the arcuate guide rails 51 for causing the plates to be 10 lifted out of contact with the conveyer chains and to be guided and supported in cooperation with the carriers in an arcuate upwardly-directed path until such plates reach a position to permit a sliding delivery 15 thereof outwardly as they are being carried upwardly by the carriers. At such delivery position, we preferably provide means for engaging and lifting the outer edge of the plates away from the carrier and then accelerating the movement of such plates outwardly with a sufficient degree of rapidity to enable the plates to be delivered or ejected from the carrier before the same moves past the delivery position or the 25 plane at which it is proposed to deliver the plates. Our engaging and lifting means for the edge of the plate preferably comprise a series of rollers 52 mounted upon the shaft 53 and driven, as shown, by sprocket 30 54, chain 55 and sprocket 56 on the main drive shaft. The shaft 53 is preferably supported on the arcuate guiding rails 51 which is adjustably mounted to move vertically, and, as shown, four of these rails, two 35 outer rails and two inner rails, are connected at one end on a shaft 57 pivoted in the casing and extend outwardly beyond the frame of the machine into proximity with the ends of the carriers and are connected 40 at their outer ends by the shaft 53 for which they form supports. For the purpose of enabling the rails to be adjusted and to be locked in any suitable adjusted position, the outer arcuate rails 51 are preferably provided intermediate their ends 45 with hubs 58 having screw-threaded pins 59 extending through slots 60 in the frame of the machine, a nut 61 being provided for locking the rail to the frame. Adjustment 50 of the rails 51 may cause a slackening of the drive chain 55 and in order to take up the slack on this chain, we preferably provide a slotted adjusting-arm 62 which is pivotally connected at 63 on the frame of the 55 machine and has at its outer end a pinion 64 adapted to mesh with the chain and to take up the slack thereof by adjustment of the arm 62. The outer arcuate rails 51 are provided at their outer ends with extensions 60 65 between which extensions is mounted a shaft 66 having mounted thereon a series of deflecting rollers 67 which engage the plate after the start of its movement and cause the same to be deflected in a slight upward

direction so as to throw the outer edge of 65 such plates outwardly and permit a falling of the same substantially horizontally or in a slightly inclined path into a pile of stack which, as shown, is formed in a box 68 so positioned that its rear wall will stop the 70 sliding movement of the edges of the plates and cause the same to be piled successively on top of each other, said box preferably being open at its top and also open at one side wall to permit the falling down of the 75 rear edge of the plates through the box without engagement with such side wall of the stacking box.

Having described our invention, we claim:—

1. In a drying apparatus of the character described, the combination with a casing, of conveyer chain mounted in said casing for conveying plates through said casing, plate-carriers mounted on said conveyer chain for 85 retaining the plates in upright position on said conveyer chain and delivery mechanism comprising means for lifting said plates out of contact with the chain and guiding the same in an arcuate path to enable said plates 90 to be slid in an inclined position off said carriers.

2. In a drying apparatus of the character described, the combination with a casing, of conveyer chain mounted in said casing for 95 conveying plates through said casing, plate carriers mounted on said chain for retaining the plates in upright position on said conveyer and delivery mechanism comprising arcuate rails adapted to cooperate with 100 the carriers to lift the plates out of contact with the conveyer chain and means at the end of said arcuate rails for lifting such plates out of contact with the carrier and causing the same to be slid outwardly in an 105 inclined direction for stacking.

3. In a drying apparatus of the character described, the combination with a casing, of conveyer-mechanism having parts moving through said casing horizontally in opposite directions and in arcuate paths at opposite ends thereof, plate-carriers mounted on said conveyer-mechanism in substantially perpendicular relationship thereto, delivery mechanism comprising pivoted arcuate rails 110 cooperating with said carriers to lift the plates out of contact with the conveyer mechanism and rollers at the ends of said arcuate rails for lifting and sliding said plates out of contact with said carriers during the 115 travel thereof in an arcuate path.

4. In a drying apparatus of the character described, the combination with a casing, of conveyer-mechanism having parts moving through said casing horizontally in opposite 120 directions and in arcuate paths at opposite ends thereof, plate-carriers mounted on said conveyer-mechanism in substantially per-

pendicular relationship thereto, delivery mechanism comprising pivoted arcuate rails cooperating with said carriers to lift the plates out of contact with the conveyer mechanism, rollers at the end of said arcuate rails for lifting and sliding said plates out of contact with said carriers during the travel thereof in an arcuate path and another series of rollers arranged outwardly of said 5 first series of rollers in the path of said plates for tilting the outer edges of such plates upwardly to permit a sliding of the same into a horizontal stacking position.

6. In a drying apparatus of the character 10 described, the combination with a casing, of conveyer mechanism moving through said casing horizontally, plate carriers mounted on said conveyer mechanism in substantially perpendicular relationship thereto and aligning rails at the sides of said plate carriers 15 adapted to engage the edges of plates in their movement by the conveyer mechanism through such casing.

7. In a drying apparatus of the character 20 described, the combination with a casing, of conveyer-mechanism moving through said casing horizontally, plate carriers mounted on said conveyer mechanism in substantially perpendicular relationship thereto and aligning rails arranged at opposite sides of said 25 plate carriers and means for simultaneously moving the opposite aligning rails toward the carriers to align the plates carried by such carriers in their passage through the 30 casing.

8. In a drying apparatus of the character 35 described, the combination with a casing, of conveyer mechanism moving through said casing horizontally, plate carriers mounted on said conveyer mechanism in substantially perpendicular relationship thereto, aligning rails pivoted on rock shafts mounted on the casing at opposite sides adjacent to the path 40 of movement of the plates, connecting rods and links for causing said rails to be moved simultaneously toward the carriers and means for turning said rocking shafts extending outside the casing.

9. In a drying apparatus of the character 45 described, the combination with a casing, of an endless conveyer chain moving in one direction through said casing horizontally and in arcuate paths at its ends, another endless conveyer chain moving parallel to and below 50 said first mentioned chain in the opposite direction, plate-carriers mounted on one of said conveyer chains in substantially perpendicular relationship thereto and means for transferring plates from one conveyer chain to the other embodying a roller having 55 grooves for the reception of the lower edges of the plates, and means for guiding the opposite edges of the plates into contact with the other conveyer chain.

10. In a drying apparatus of the character 60 described, the combination with a casing, of an endless conveyer chain moving in one direction through said casing horizontally and in arcuate paths at its ends, another endless conveyer chain moving parallel to and below 65 said first mentioned chain in the opposite direction, plate carriers mounted on one of said conveyer chains in substantially perpendicular relationship thereto, means for transferring plates from one conveyer chain to the other embodying a roller having 70 grooves for the reception of the lower edges of the plates and guide rails for guiding the opposite edges of said plates into contact with the other conveyer chain.

11. In a drying apparatus of the character 75 described, the combination with a casing, of an endless conveyer chain moving in one direction through said casing horizontally and in arcuate paths at its ends, another endless conveyer chain moving parallel to and below 80 said first mentioned chain in the opposite direction, plate carriers mounted on one of said conveyer chains in substantially perpendicular relationship thereto, means for transferring plates from one conveyer chain to the other embodying a roller having 85 grooves for the reception of the lower edges of the plates and guide rails for guiding the opposite edges of said plates into contact with the other conveyer chain.

12. In a drying apparatus of the character 90 described, the combination with a casing, of conveyer-mechanism having parts moving through said casing horizontally in opposite directions and in arcuate paths at opposite 95 ends thereof, plate-carriers mounted on said conveyer-mechanism in substantially perpendicular relationship thereto and adjustable closure means for closing the space between the side edges of the plates and the 100 side walls of the casing.

13. In a drying apparatus of the character 105 described, the combination with a casing, of conveyer-mechanism moving through said casing horizontally, plate carriers mounted on said conveyer mechanism in substantially perpendicular relationship thereto, aligning rails arranged at opposite sides of said plate carriers, means for simultaneously moving opposite aligning rails toward the carriers to align the plates carried by such carriers in their passage through the casing and doors pivoted at one side edge on said aligning rails and at the other side edge on the casing.

14. In a drying apparatus of the character 120 described, the combination with a casing, of conveyer-mechanism having parts moving through said casing horizontally in opposite directions and in arcuate paths 125

at opposite ends thereof, plate-carriers mounted on said conveyer-mechanism in substantially perpendicular relationship thereto and stationary rods extending parallel to said conveyer mechanism for guiding in combination with said carriers a plate or plates that may fall off such conveyer mechanism.

14. In drying apparatus of the character described, the combination with a casing, of an endless conveyer chain moving in one direction through said casing horizontally and in arcuate paths at its ends, another endless conveyer chain moving parallel to and below said first mentioned chain in the opposite direction, plate-carriers mounted on one of said conveyer chains in substantially perpendicular relationship thereto, means for transferring plates from one conveyer chain to the other embodying a roller having grooves for the reception of the lower edges of the plates, means for guiding the opposite edges of the plates into contact with the other conveyer chain and ejecting arms arranged to intersect the arc described by the bottom of the grooves for positively ejecting the plates therefrom.

In witness whereof, we have signed our names to the foregoing specification in the presence of two subscribing witnesses.

CHARLES WAGNER.
